UNITED STATES PATENT OFFICE.

CHARLES F. VERRELL, OF GRAND RAPIDS, MICHIGAN.

GRAIN DRIER AND COOLER.

SPECIFICATION forming part of Letters Patent No. 726,805, dated April 28, 1903.

Application filed February 28, 1903. Serial No. 145,586. (No model.)

To all whom it may concern:

Be it known that I, CHARLES F. VERRELL, a citizen of the United States, residing at Grand Rapids, in the county of Kent and State of Michigan, have invented certain new and useful Improvements in Grain Driers and Coolers, of which the following is a specification.

My invention relates to improvements in machines for drying grains after having been washed, cooked, and scoured in the process of manufacturing pure foods; and its objects are, first, to provide a grain-drier with which grain may be thoroughly dried and cooled by the one process, and, second, to economize in time, space, and expense in the construction of these driers. I attain these objects by the mechanism illustrated in the accompanying drawings, in which—

20 Figure 1 is an elevation of my machine with a part of the case cut away to show the relative positions of its several parts. Fig. 2 is a sectional plan of the same on the line X X of Fig. 1, showing the steam-coil and a portion of the lower cylinder. Fig. 3 is a back end elevation of the case, showing the ends of the cylinders. Fig. 4 is a sectional elevation of one of the cylinders on the line y y of Fig. 3. Fig. 5 is a sectional end view 30 of the same on the line Z Z of Fig. 4.

Similar letters refer to similar parts throughout the several views.

Having constructed proper supporting-frames, as indicated at J J, I construct cylinders B B' upon shafts G and support the shafts in the supporting-frames, substantially as indicated in Fig. 1, and secure the cylinders in an inclosing compartment A. These cylinders are constructed by placing heads 40 F and F' upon the shafts G and covering these heads and the space between them at their peripheries with a finely-woven wire cloth or gauze b', which is securely attached at the end to the rings b, so that it will retain its shape when in the process of drying or cooling grain.

The heads F are constructed with a hole through the center, as at f in Figs. 3 and 4, so that the lower ends of the hoppers D and D' may enter, as indicated in Figs. 1 and 4, for the purpose of conducting the grain into the cylinders. To support these heads, I

set the hub g off from the surface and connect the head and hub by curved arms f', so that the lower ends of the hoppers D and D' 55 will project well into the cylinders and deposit the grain a safe distance from the head, as indicated by the arrows in Fig. 4. The heads F' are provided with openings f'' at the periphery, so that the grain may pass freely 60 through, and I place inwardly-projecting wings H upon the inner surface of the roll, as indicated in Figs. 4 and 5, which act a double purpose—first, to support the gauze covering, and, second, to carry the grain up 65 beyond the vertical center of the roll, so that it will be constantly circulating in the roll as it revolves.

I set the cylinders upon an angle of about five degrees, the cylinder B being above the 70 cylinder B' and inclining downward from the hopper D toward the hopper D' and the cylinder B' inclining downward from the hopper D' to the hopper D'', where the grain is discharged from the cylinder B', so that grain 75 that enters the cylinder B at D will be constantly carried upward as the cylinder revolves until it slides from the wings H, when it will fall to the lower side of the cylinder upon a slight angle with the cylinder that 80 keeps it constantly moving toward the lower end of the cylinder, where it is discharged into the upper end of the hopper D' and is conducted into the upper end of the cylinder B', when by the process hereinbefore described 85 in connection with the cylinder B it is constantly moving toward the hopper D'', where it is discharged from the cylinder.

The cylinders are made to revolve, first, by a belt passing around the pulley G' or by any 90 other of the well-known means of transmitting a rotary motion to machinery, and, second, by a connecting belt-sprocket or any other of the well-known mechanical devices for transmitting power from one machine to 95 another, a simple form being indicated at II' in Fig. 1.

To dry the grain after it has been washed, &c., I place a steam-coil C within the case A and under the upper cylinder, so that air 100 passing through the case, as indicated by the upwardly-inclined arrows in Fig. 1, will be thoroughly heated and will circulate freely in the cylinder B around and through the con-

stantly-falling grain in such a manner as to thoroughly dry it by the time it has traveled the length of the cylinder and is discharged into the hopper D', and for cooling the grain 5 while it is passing through the cylinder B', I force a blast of cold air into the inclosing case below this cylinder, as indicated by the arrows passing through the blower E, which passes through the cylinder and intermingles 10 freely with the grain as it is being conducted through the cylinder, as hereinbefore explained. By this means the lower cylinder and its contents are cooled by the same blast of air that afterward passes through the 15 steam-coil and is heated and thence passing through the cylinder B and out of the vents a dries the grain in the cylinder B.

The hopper D may be made with simply an aperture for the passage of the shaft G; 20 but I prefer that it be divided and provided with a slat d, as shown in Fig. 3, as with this construction it may be readily removed and replaced.

Having thus fully described my invention, 25 what I claim as new, and desire to secure by Letters Patent of the United States, is—

1. In a grain drying and cooling machine an inclosing case in combination with cylinders set one above the other and converging 30 toward a given point, the cover of said cylinders being made of finely-woven wire-gauze, hoppers for conducting grain into and out of said cylinders, a steam heating-coil below the upper cylinder and a forced-cold-blast 35 fan below the lower cylinder, substantially as and for the purpose set forth.

2. In a grain drying and cooling machine, an inclosing case, revolving cylinders within said case said cylinders supported upon shafts 40 and having receiving and discharge heads sup-

porting the casing, a casing constructed of finely-woven wire-gauze, the receiving-heads having an opening through the center and hubs and inwardly-curved arms connecting it with the shaft, the discharge-heads having 45 apertures at their peripheries, radial wings attached to and connecting said heads near the periphery, the cylinders stationed one above the other and converging toward a given point, a steam heating-coil between the 50 cylinders, a cold-blast fan below the lower cylinder, hoppers leading to the upper cylinder and from the lower cylinder at one end and connecting the cylinders at the other end, and driving mechanism connected with 55 the cylinders, substantially as and for the purpose set forth.

3. In a grain drying and cooling machine an inclosing case cylinders within the inclosing case situated one above the other and 60 converging toward a given point, the walls of said cylinder constructed of fine wire-gauze heads supporting said gauze and having openings for the passage of grain-wings converging from the inner surface of the cylinder 65 toward the center, shafts supporting said cylinders and driving mechanism connected therewith, retaining-rings encircling the cylinders, hoppers leading to and from the cylinders, a heating-coil between the cylinders 70 and a cold-blast fan below the lower cylinders, substantially as and for the purpose set forth.

Signed at Grand Rapids, Michigan, February 25, 1903.

CHARLES F. VERRELL.

In presence of—

NELLIE CILLEY,
ITHIEL J. CILLEY.
